United States Patent Office

Des. 203,041
Patented Nov. 30, 1965

203,041

SEAT

Edward V. B. Regan, 20 Melbourne Place, Buffalo, N.Y.

Filed Aug. 31, 1964, Ser. No. 81,535

Term of patent 14 years

(Cl. D15—1)

FIG. 1.

FIG. 2.

FIG. 3.

FIG. 4.

FIG. 5

FIG. 6.

FIG. 1 is a front elevational view of a seat, showing my new design therefor;

FIG. 2 is a side elevational view thereof;

FIG. 3 is a top plan view thereof;

FIG. 4 is a rear elevational view thereof;

FIG. 5 is a bottom plan view thereof, on a reduced scale; and

FIG. 6 is a front perspective view thereof.

The side not shown is identical to the side shown in FIG. 2.

I claim:

The ornamental design for a seat, substantially as shown and described.
